CHECK BOOK

Application filed February 27, 1928. Serial No. 257,376.

My invention relates to check books of the foldable pocket type and consisting of a cover and a check pad, the latter being made up of a multiplicity of checks bound together by 5 wire staples extending through the check stubs and a sheet of fabric glued to and covering the edge of the stubs to conceal the staples, but primarily designed to attach a cardboard flap to the pad employed for retaining the pad within a pocket of the cover.

In check books of this general character the expense involved in the binding of the checks into pad form and the attaching of the retaining flap is relatively high, and 15 greatly increases the cost of manufacture of such an article, while an additional manufacturing expense is incurred by the necessity arising of providing in the pad a pocket for the retaining flap in addition to the pass-book receiving pocket. Further, the check pad is not designed for nor is it capable of 20 displacement from the cover without detachment but is intended to and does remain superimposed on the cover when unfolded for writing. Due to the folds of the cover, the checks cannot be flattened out when extended on the cover, and, consequently, an undulated surface is presented which renders it difficult to write on legibly.

It is a purpose of my invention to provide a check book which purports to appreciably 25 reduce the cost of binding the checks into pad form, and to attach the pad to the cover in a different manner to the elimination of the attaching flap and the corresponding pocket and to permit the check pad to be removed from the cover and placed flatwise for writing and without actually detaching the pad from the cover so that it will not become accidentally detached from the cover and can 30 be readily returned to its original position within the cover.

I will describe only one form of check book embodying my invention and will then point out the novel features in claims.

Fig. 1 is a view showing in top plan one form of check book embodying my invention in extended or unfolded position;

Fig. 2 is a longitudinal sectional view showing the check book in folded position;

Fig. 3 is an enlarged fragmentary perspective view showing the check pad within, but detached from the cover; and

Fig. 4 is a perspective view showing the check book in extended position for writing.

In carrying out my invention, I provide as an article of manufacture a check pad P which comprises a plurality of checks 15 and their accompanying stubs 16 secured in stacked formation to form a pad by the provision of a head member 17 having a two-part shank 18 extended through and secured in the stubs 16 so as to firmly secure the checks in pad form. The head member 17 is exposed at the upper side of the pad to permit engagement with a companion socket member 19 having a two-part shank 20 shown as secured in a cover K. The socket member 19 is secured within a flap 21 on one end of the cover K, and one part of the shank 20 is constructed to provide what may be termed a button disposed at the outer side of the flap as shown in Figs. 1 and 4.

The cover K is made of any suitable material such as leather or fabric and is of such dimensions as to receive the check page P and form not only the flap 21 but a closure flap 22 having a socket member 23 adapted to engage and receive a head member 24 to secure the flap in the position shown in Fig. 2 and in which the check book as a whole is retained in folded or closed position. The cover K is provided with a single pocket 25 in which is adapted to be received the pass-book indicated at 26. However, no pocket for the reception of a retaining flap of the check pad is necessary in this cover by reason of the means provided for securing the check pad within the cover.

As shown in Fig. 3, the check pad P is adapted to be positioned within the cover so that a portion of the stub end thereof will be disposed beneath the flap 21 when the latter is folded, as shown in Figs. 1 and 2, whereby the socket member 19 can be pressed downwardly to force the head member 17 thereinto and thereby secure the check pad to the flap and in proper position within the cover. It will be understood that the head and socket members 17 and 19 constitute the

two parts of a conventional snap fastener and that when the head member is once forced into the socket member it is retained against accidental displacement yet permitting relative rotation of the two parts. When the check book is folded, as illustrated in Fig. 2, the check pad continues to be secured to the cover, as the folding of the check pad and cover is ineffective to dislodge the head member from the socket member.

When desiring to use the check pad for the filling in of a check and the corresponding stub, the pad is extended from the cover without detachment therefrom so that the pad assumes what may be termed an end-to-end position with respect to the cover as illustrated in Fig. 4. With the cover removed from beneath the pad it will be manifest that the pad can be flattened to present an even surface upon which to write. If the pad is not at an angle convenient for writing with respect to the cover, the rotative movement permitted through the coaction of the head and socket members 17 and 19 will allow the pad to be shifted to any angular position.

In returning the check pad to its original position within the cover it is only necessary to first longitudinally align the cover with respect to the pad when the latter can be swung inwardly beneath the pad, the flap 21 serving as a hinge connection between the pad and cover. That portion of the cover defined by the transverse fold between the flap 21 and the main body of the cover functions in conjunction with the separable fastener 17 and 19 to secure the pad against edgewise displacement within the cover. However, with movement of the cover to the extended position shown in Fig. 4, the check pad is free to be swung in the plane of itself to any angular position desired and without separating the parts of the fastener and hence maintaining the check pad physically connected to the cover.

It will be understood that when all of the checks 15 have been torn from the stubs 16 and it is desired to remove the stubs, it is only necessary to separate the parts 17 and 19 of the fastener, and the head member 17 can be used in conjunction with other socket members to secure the stubs in fixed position with a suitable container which may be provided for the purpose.

Although I have herein shown and described only one form of check book embodying my invention, it is to be understood that various changes and modifications may be made herein without departing from the spirit of the invention and the spirit and scope of the appended claims.

I claim:

1. A check book having a check pad including stubs, a cover therefor, one end of which is inturned to form a flap beneath which the stub end of the check pad is re-

ceived, and a separable fastener having one part secured to the stub end of the check pad and the other part secured to said flap to be engaged by the first part and retain the check pad on the flap so that in the normal position of the flap the check pad is held within the cover but when unfolded or extended the check pad may be extended from the cover so as to occupy an end-to-end position thereto.

2. A check book as embodied in claim 1 wherein that part of the fastener secured to the check pad is extended through all check stubs of the pad to hold the checks in pad form.

3. A check book as embodied in claim 1 wherein the parts of the fastener when engaging each other are relatively rotatable about a common axis to allow the check pad when extended to be moved to various angular positions with respect to the cover.

Signed at Los Angeles, in the county of Los Angeles and State of California, this 10th day of February, 1928.
